UNITED STATES PATENT OFFICE.

FRANKLIN L. MENESEE, OF AURELIA, IOWA.

REEL FOR CHECK-ROW CORN-PLANTERS.

SPECIFICATION forming part of Letters Patent No. 415,464, dated November 19, 1889.

Application filed August 9, 1889. Serial No. 320,279. (No model.)

To all whom it may concern:

Be it known that I, FRANKLIN L. MENESEE, residing at Aurelia, in the county of Cherokee and State of Iowa, have invented certain new and useful Improvements in Check-Row Corn-Planters, of which the following is a specification.

My invention relates more particularly to a reel for unwinding or taking up the check-wire and means for automatically shifting the wire as it is wound upon the reel.

To this end my invention consists in the peculiar combination and novel arrangement of parts, all of which will hereinafter be fully described in the annexed specification, and particularly pointed out in the claims, reference being had to the accompanying drawings, in which—

Figure 1 is a top plan view of the truck-frame of a check-row corn-planter with my improvements in position. Fig. 2 is an elevation of the reel and wire-shifting devices. Fig. 3 is a top plan view of a portion of the same. Fig. 4 is a longitudinal section of the reel. Fig. 5 is a cross-section of the same on the line 5—5, Fig. 4. Fig. 6 is a detail view of a portion of the reel-supporting bar and its bearing-box, and Figs. 7 and 8 are detail views of modifications hereinafter referred to.

In the practical construction of my invention I journal my improved reel upon a transverse bar mounted to rotate in the rear end of the truck-frame of a check-row corn-planter, said bar being preferably the marker-bar, the drawings and the description in the present case specifically referring to a novel construction of marker which forms the subject-matter of a separate application filed April 6, 1889, Serial No. 306,263.

In order to more clearly describe and illustrate my present invention, I have illustrated the means shown in the aforesaid application for operating the marker-bar.

Referring to the accompanying drawings, A indicates the main frame, which is mounted upon the drive-wheels B B in the usual manner.

C denotes a gear-wheel secured upon the inner face of the hub of one of the drive-wheels B, which engages a gear D on the outer end of a short shaft E, mounted in the frame

A, and which is provided at its inner end with a double bevel-gear F, which meshes with a similar gear G upon one end of the longitudinal shaft H, mounted in the frame A, as shown. Upon one end of this shaft is mounted a sliding gear e, which when adjusted for operation engages an idler-gear d, journaled upon the frame, with which engages a gear c upon a shaft a, mounted in the frame near one of the rear ends, as shown.

The rear ends of the side beams of the frame are extended, as at A² A², and form bearings A³ for circular disks L L, held to rotate in said bearings, which are each provided with a central squared aperture L' L', in which the marker-bar K is held to slide. Each of the disks L L is provided with a collar L² on its outer face and a bevel-gear L³ on its inner face, by means of which they are prevented from lateral movement in their bearings. One of said bevel-gears meshes with a bevel-gear b on the outer end of the short shaft a, and from it receives the motion whereby the marker-bar or reel-supporting bar K is revolved. Each of the disks L L is also provided with lateral extensions or sockets L⁴ L⁴, which form additional bearings for the bar K, and also serve to automatically raise the marking devices when said bar is used as a marker.

Before specifically describing my improved reel and wire-shifting devices I will state that when the said bar is used as a marker-bar the marking devices are supported at the ends of said bar, said devices being preferably constructed in the manner shown and described in my other application referred to, and when said bar is to be used as a support for the reel the marking devices are held up out of operative position. I would further state that the said marker-bar may be reciprocated in its bearings to either side of the machine, and to hold same from revolving when it is desired to shift said bar from side to side I provide one of the collars L² with a recess 12, with which engages a gravity-pawl 11 pivoted to the frame, as most clearly shown in Fig. 6 of the drawings.

f denotes the reel, which consists of the hub portion g, provided with a central squared aperture h, and the reel portion i,

which fits on the hub portion, as shown in Fig. 4. The hub g extends laterally to each side of the reel, as at $g' g'$.

$j j$ denote spring-plates secured at one end 5 to the sides of the reel i , which pass over and embrace the hub-sections $g' g'$, and have their outer ends adjustably connected by means of the thumb-screw k^6 , the object of providing said spring-plates appearing far-ther on.

In adjusting the reel in position the same is slid onto the bar K and held thereto by means of the set-screw m passing through a lip or projection m' on the hub-section and 15 engaging the bar K .

N denotes the automatic device for moving the wire into proper position while it is being wound upon the reel. Said device consists of a skeleton frame N' , which is detachably secured to either of the end projections $A^2 A^2$ 20 of the frame, in which is mounted a vertical shaft n , provided with a bevel-gear n' at its lower end, adapted to engage the bevel-gear L^3 on one of the disks L , said frame and shaft 25 being suitably braced in position by the bar o , as shown.

O denotes a bracket projected laterally from the frame N , in which is journaled a gear-wheel P , which meshes with a worm Q 30 on the shaft n . Disposed in front of the gear-wheel P and adapted to reciprocate backward and forward in bearings formed by a bracket s on the frame N , and in outwardly-projecting arms $t t$ secured thereto, is a rod S , which 35 is provided with a projecting stud S' , adapted to engage with a cam-groove R in the front face of the gear-wheel P .

The outer end of the rod S is connected to a swinging arm U , pivoted to a circular 40 bracket T , fixed on the outer ends of the arms $t t$, the lower end of which is forked at $U' U'$ and provided with friction-rollers u , as shown. The lower end engages the wire in a manner clearly shown in Fig. 2 of the drawings.

V denotes a brace-rod provided with a forked rear end v , which engages the rod K when the strain of said rod is forward, the forward end of said arm engaging the frame, 50 as shown. The rod V is also provided with a loop v' at said end, which engages the bar K when the strain is in a rearward direction.

When the reel is adjusted in position to take up the wire, the end of the wire will be 55 passed over the reel and secured thereto. Now when the planter travels in a forward direction the intermediate gearing devices will be revolved by the wheel B and the cog-wheel C in the direction indicated by the arrows, 60 thereby revolving the disks $L L$ and the bar K , which in turn will revolve the reel in the rearward direction and thereby take up the wire. During this operation the wire-shifting devices will be operated by the bevel-gear L^3 65 on the disk L and cause the swinging arm U to gradually move back and forth

in front of the reel and shift the wire, so that the same will be evenly wound on the reel.

It will of course be understood that the several gearing devices are so adjusted in relation to each other that the reel will revolve at the proper speed to gradually take up the wire during the continued movement of the planter. The shifting devices are also so adjusted that they will feed back and forth as 75 the wire fills up on the reel in layers. As the wire fills up the reel and one layer has been wound thereon, it will be observed that the mean diameter of the reel will have been increased and that the wire will then wind 80 up at a faster speed. As it, however, is necessary that the same should always wind thereon at the same degree of speed, I form the reel of two sections or portions, as before stated.

By the said construction of reel it will be seen that should the wire exert any increased tension on the reel the reel portion proper will slip backward on the hub portion and thereby equalize the take-up speed of the 90 reel. The friction of the reel on the hub portion may be adjusted by the spring-plates $j j'$.

When it is desired to unwind the wire to place same in position in the field, the sliding gear e is slid out of operative position, and the reel is inserted on the rod K , so the wire will feed out from the under side thereof. When the reel is adjusted in this position, the strain of the bar will be rearward and the brace-bar 100 V will be hooked over the bar, as before stated, to relieve the said bar from strain.

It will be understood that the reel and the wire-shifting devices may be adjusted to operate on either side of the machine.

In adjusting my improvements to a planter-frame of ordinary construction I provide detachable metal bearings A^6 , which are secured to the frame A in the manner clearly shown in Fig. 7 of the drawings, and which 110 form the bearings for the circular disks L . When I employ the said metal bearings, I also prefer to construct the wire-shifting devices in such a manner that the circular bracket T will be disposed horizontally over the wire 115 reel, as clearly shown in Fig. 8 of the drawings.

From the foregoing description, taken in connection with the drawings, the operation and advantages of my improvement will be readily understood. It will be seen that the 120 same may readily be adjusted to the truck-frames of corn-planters, and that the operation thereof is exceedingly simple and effective for its desired purpose.

Having thus described my invention, what I 125 claim, and desire to secure by Letters Patent, is—

1. The combination, with a bar mounted to rotate in the main or truck frame of a check-row corn-planter, said bar extended to one 130 side of said frame, and the intermediate gearing mechanism between said bar and one of

the drive-wheels, of a reel adapted to be slid onto said extension to revolve therewith, substantially as and for the purpose described.

2. The combination, with a bar held to rotate in the truck-frame of a check-row corn-planter, one end of said bar projected to one side of the frame, and means for rotating said bar, of a reel detachably held on said extended portion of the bar to turn therewith and a brace-bar secured at one end to the main frame, its opposite end arranged to engage the outer end of the reel-holding bar, substantially as and for the purpose shown and described.

15 3. The combination, with a bar held to rotate in the truck-frame of a corn-planter and means for rotating said bar, said bar extended to one side of the frame, of a reel mounted on said extension to turn therewith, a wire-shifting device mounted on the frame and operating to the front of the reel, and intermediate gearing between the reel-bar and the said shifting devices, whereby said devices are operated substantially as and for the purposes described.

4. The combination, with the main frame, the wheels B B, revolving bearing-disks L L, mounted in the ends A² A² of the frame, said disks provided with transverse squared apertures, intermediate gearing devices between one of said disks and one of the drive-wheels for revolving said disks, and a marking-bar held to slide transversely in said disks and adapted to be projected to either side of the machine, of the reel f, consisting of an apertured hub adapted to fit upon the extended end of the marking-bar, and a reel portion i, fitted upon the hub portion, and friction-plates j, secured to the hub and reel sections for 40 adjusting the frictional contact of said parts, substantially as and for the purpose described.

5. The combination, with the main frame A, the drive-wheels B B, the revolving disks L L, journaled in the rear ends of the frame, having transverse apertures, said disks provided with bevel-gears L³ L³, intermediate gearing devices, substantially as shown, between one of the gears L³ and one of the drive-wheels, and the marking-bar held to slide in 50 said disks L L, said bar adapted to slide to

either side of the machine, of a reel mounted on the extended end of the bar and adapted to revolve therewith, and automatic wire-shifting devices operating in front of the reel, adapted to shift the wire back and forth in front of the reel during winding, said device mounted on the frame and provided with a gear engaging one of the gears L³, whereby said devices are operated, substantially as and for the purpose shown and described.

6. The combination, with the main frame, the revolving disks L L mounted therein, provided with gears L³ L³, means, substantially as shown, for revolving said disks, the marker-bar K, held in said disks and adapted to be slid to either side of the machine, and the wire-reel f, mounted on the said bar K and adapted to revolve therewith, of the wire-shifting attachments, consisting of a frame N', detachably mounted on the frame, a vertical shaft n, mounted in said frame N', provided with a worm Q and a bevel-gear engaging one of the gears L³ on the disks, a cog-wheel P, journaled in the frame N', meshing with the worm Q, said wheel provided with a cam-groove, a reciprocating shaft S, journaled in the frame N', provided with a stud S', engaging the cam-groove, and a swinging arm U, pivoted at its upper end to the frame, connected below its pivot with the shaft S, the lower end depending in front of the reel and provided with forked arms, all arranged substantially as shown, and for the purpose described.

7. The combination, with the frame A, the revolving disks L L, the intermediate gear devices between said disks and one of the drive-wheels, said disks provided with transverse apertures, the marker-bar K, held to slide in said disks, and the reel f, mounted on the extended end of the said bar, of the brace-rod V, provided with a forked end v and a loop v', adapted to engage the end of the bar K, its opposite end adapted for connection with the frame A, substantially as and for the purpose described.
